UNITED STATES PATENT OFFICE

141,308

DESIGN FOR A FORK OR ANALOGOUS ARTICLE

Harold E. Nock, Newburyport, Mass., assignor to
Towle Manufacturing Company, Newburyport,
Mass., a corporation of Massachusetts

Application October 24, 1944, Serial No. 115,948

Term of patent 14 years

(Cl. D54—12)

To all whom it may concern:

Be it known that I, Harold E. Nock, a citizen
of the United States, residing at Newburyport,
in the county of Essex and Commonwealth of
Massachusetts, have invented a new, original,
and ornamental Design for a Fork or Analogous
Article, of which the following is a specification,
reference being had to the accompanying draw-
ing, forming a part thereof.

In the accompanying drawing,

Figure 1 is a front view of a fork showing my
new design; and

Figures 2, 3 and 4 are sectional views on the
lines 2—2, 3—3, and 4—4, respectively, of Fig-
ure 1.

The essential features of my design reside in
the parts shown in full lines.

The design is illustrated as embodied in the
handle of a fork, but it may also be embodied in
or applied to other handles of like nature.

I claim:

The ornamental design for a fork or analogous
article, substantially as shown and described.

HAROLD E. NOCK.
